[57] CLAIM

The ornamental design for a desk top panel, as shown and described.

DESCRIPTION

FIG. 1 is a perspective view of a desk top panel, showing our new design;

FIG. 2 is a front elevational view of the embodiment shown in FIG. 1;

FIG. 3 is a rear elevational view of the embodiment shown in FIG. 2;

FIG. 4 is a left side elevational view of the embodiment shown in FIG. 1;

FIG. 5 is a top plan view of the embodiment shown in FIG. 1;

FIG. 6 is a right side elevational view of the embodiment shown in FIG. 1;

FIG. 7 is a perspective view, showing a second embodiment of our new design;

FIG. 8 is a front elevational view of the embodiment shown in FIG. 7;

FIG. 9 is a rear elevational view of the embodiment shown in FIG. 7;

FIG. 10 is a right side elevational view of the embodiment shown in FIG. 7;

FIG. 11 is a left side elevational view of the embodiment shown in FIG. 7;

FIG. 12 is a top plan view of the embodiment shown in FIG. 7;

FIG. 13 is a perspective view, showing a third embodiment of our new design;

FIG. 14 is a front elevational view of the embodiment shown in FIG. 13;

FIG. 15 is a rear elevational view of the embodiment shown in FIG. 13;

FIG. 16 is a right side elevational view of the embodiment as shown in FIG. 13;

FIG. 17 is a left side elevational view of the embodiment as shown in FIG. 13;

FIG. 18 is a top plan view of the embodiment shown in FIG. 13;

FIG. 19 is a perspective view of the embodiment shown in FIG. 13 but showing the hinged front portion of the desk top in an open position;

FIG. 20 is a perspective view, showing a fourth embodiment of our new design;

FIG. 21 is a front elevational view of the embodiment shown in FIG. 20;

FIG. 22 is a rear elevational view of the embodiment shown in FIG. 20;

FIG. 23 is a left side elevational view of the embodiment shown in FIG. 20;

FIG. 24 is a top plan view of the embodiment shown in FIG. 20; and,

FIG. 25 is a right side elevational view of the embodiment shown in FIG. 20.

The broken lines in FIGS. 1, 7, 13 and 20 are for environmental purposes only and form no part of the claimed design.
